UNITED STATES PATENT OFFICE.

CHARLES E. HOPKINS, OF NEW YORK, N. Y.

MACHINE FOR FINISHING STEREOTYPE PRINTING-PLATES.

1,346,601.

Specification of Letters Patent.

Patented July 13, 1920.

Original application filed February 25, 1911, Serial No. 610,834. Divided and this application filed April 2, 1917. Serial No. 159,117.

To all whom it may concern:

Be it known that I, CHARLES E. HOPKINS, a citizen of the United States, residing at New York, in the county of New York and 5 State of New York, have invented a new and useful Machine for Finishing Stereotype Printing-Plates, of which the following is a specification.

This is a division of my application on a 10 machine for making stereotype plates, filed February 25, 1911, Serial No. 610,834.

My invention is for the purpose of finishing semi-circular curved stereotype printing plates for use on the cylinders of rapid 15 printing or rotary presses, particularly such as are in common use in producing newspapers, and is designed mainly as a labor saving device whereby one man by manipulating certain handles and levers will be able 20 to produce the stereotype printing plates completely finished, and cooled so they can be handled by the bare hands, in condition to be immediately attached to the printing press cylinder; also to provide means where- 25 by, through the control of the contraction of the curved printing plate during the process of cooling, the operator will be able to produce plates of various curvatures or dimensions from the same casting chamber and 30 further, through the control of the cooling fluid, deliver the plates practically dry and ready to be attached to the press cylinders.

More specifically the invention comprises a practicable, simple and convenient mechanism in alinement with the core when it reaches its final open position for receiving the plate therefrom, shaving the ribs cast on the concave surface of the plate, cutting off the riser, beveling the riser and, gradu- 35 ally lowering and finally dropping the tail cut off, releasing the plate and allowing it to be fed by gravity from the finishing mechanism to a final cooling mechanism; to provide simple and effective means for re- 40 ceiving the plate from the finishing mechanism and cooling it in such a way as to control the contraction of the plate during the cooling process so that plates both of less or of greater diameter can be provided from 45 the same casting chamber; also to provide for controlling the cooling water so that the plate can be delivered dry and ready for the press cylinders.

The invention also involves numerous im- 50 provements in details of construction and

in mechanism for carrying out the objects elsewhere specified herein. Further objects and advantages of the invention will appear hereinafter.

Reference is to be had to the accompanying drawings in which—

Figure 1 is a side elevation of a complete machine constructed in accordance with this invention;

Fig. 2 is a plan of the shaving mechanism 65 with the arch removed;

Fig. 3 is a side elevation of the plate lifter support thereof;

Fig. 4 is a plan of the cam plate;

Fig. 5 is an end elevation of a stationary 70 cam;

Fig. 6 is a transverse sectional view showing how the cast plate is supported on the lifter;

Fig. 7 is a sectional view on the line 7—7 75 of Fig. 2;

Fig. 8 is a sectional view on the line 8—8 of Fig. 2;

Fig. 9 is a diagrammatic sectional view of the same on reduced scale showing one position of the parts during the finishing operation;

Figs. 10, 11, 12 and 13 are similar views showing other positions of the same parts;

Fig. 14 is a side view of the cooling ap- 85 paratus;

Fig. 15 is a fragmentary detail thereof;

Fig. 16 is a sectional view of the same on the line 16—16 of Fig. 1;

Fig. 17 is an enlarged sectional view on 90 the same line showing how the edge of the plate is held during one period of the operation.

Figs. 18 and 19 are similar views showing other positions of the plate;

Fig. 20 is an end view of one of the rollers 95 for supporting the plate with parts in section, and

Fig. 21 is a transverse sectional view on the line 21—21 of Fig. 14.

In order to get a general idea of the invention it may be stated that the drawings, particularly Fig. 1, show a machine embodying the following elements, namely, a melting furnace and pump A of any desired construction for delivering metal in measured quantities to a segmental back B preferably located in vertical position on a base or frame C, also a convex core D constituting with the back the lateral walls of the casting 105 110 115

box, but capable of moving out of the back with the cast plate thereon, and delivering the plate to a finishing mechanism E which in turn delivers it to a cooling device F. 5 The base C and the base G of the cooling device support a frame H on which the finishing mechanism is mounted. A motor K is shown for the purpose of operating certain of the parts as will appear hereinafter.

10 I will first explain the mechanism shown for shaving the ribs P' cast on the concave surface of the stereotype plate P, the mechanism for cutting off the riser and beveling that curved end, and the means for conveying 15 the now finished stereotype plate from the finishing mechanism to the cooling mechanism F, all represented in a general way by the letter E, (Fig. 1).

Mounted in three bearings 57 (Fig. 2) on 20 the frames H and G is a longitudinal main shaft 58 operated from the motor K as will be explained hereinafter. Fastened to the main shaft and within the arch is a shaving knife 59 which extends lengthwise and is of 25 a length slightly longer than the said arch, the said knife being so positioned as to engage and smooth off the faces of the ribs P' cast on the stereotype concavity.

Positioned on the main shaft beyond the 30 arch are adjustable plate stops 60 and 61 (Fig. 8) which engage ledges P² cast on the side of the concavity of the riser of the stereotype plate and stop said plate in proper position when moved into the arch, 35 from off the core, on which it has been cast and hold the said plate from further lateral movement until the lifters have raised it against the dome of said arch. The stop 61 is spring actuated because the plate enters 40 the arch out of horizontal alinement with the axis thereof and has to be moved sideways and into axial alinement when lifted up into the dome of said arch in position to be shaved, as will appear hereinafter.

45 The main shaft is caused to make one revolution each time a foot trip or pedal 159 is pushed down and released to operate a clutch jaw 133. During the revolution of the main shaft a stereotype plate is shaved 50 and the riser cut free from the said plate, by tools carried by the said shaft, which engage the stereotype plate when positioned in the stereotype plate supporting arch 64, which is mounted on the top of the frame and axially alined with the said main shaft. 55

Beneath each straight side of the arch 64 are mounted supporting and guiding rollers 65 and beyond the arch but carried by the main shaft, by reciprocating studs 66 operating in bearings 67 are a group of three rollers 68 (Fig. 4). These are caused to move 60 toward or away from the axis of the said main shaft by pins 69 on each stud engaging in grooves 70 cut in a cam plate 71. The latter moves axially on the said shaft and is

operated by a stationary face cam 72 fastened to the upper bearing 57 of the main shaft, through a connecting rod 73 a cam arm 74, and a spring 75. See Figs. 2, 4, 5 and 9. The reason for making the rollers 70 move toward the axis of the main shaft when the shaft starts to revolve is to move the rollers from under the edges of the riser of the stereotype plate resting upon the said rollers within the arch, the movement being 75 accomplished by the end of the cam arm, 74 moving out of the recess in the fixed face cam. Upon the finish of the revolution of the main shaft the spring 75 mounted upon the connecting rod moves this rod to the left 80 in Fig. 2 as the arm 74 enters a depression in the cam 72. This carries the cam plate 71 to the left and pushes the rollers out, and the rollers become a support for the stereotype plate as it moves out of the arch and 85 toward the cooling mechanism.

Beneath one side of the supporting arch is a mechanism for lifting the stereotype plate into position against the arch dome. As will be seen by the drawings the rollers 90 65 which support the stereotype plates are located out of horizontal alinement with the axis of the arch and a recess is formed beneath one side of the arch. At one side of the arch beneath this recess double flanged 95 rollers 77 are located. The purpose of these flanges is to guide the stereotype plate as it moves into position within the arch and over a plate lifter 80. (Fig. 3). This plate lifter moves in cam ways 81 fastened to the frame at an angle and as the lifter rises, it also moves toward the axis of the arch and a lip 82 (Fig. 6) formed on the seat 83 of the lifter engages in the groove P³, cast in the edge of the stereotype plate, as the lifter 100 moves upward. This forces the said stereotype plate to move at the same angle as the lifter so that the plate is moved solidly against the opposite side of the arch simultaneously with its rise. Upon the return movement, the lip 82 engaged in the groove formed on the stereotype plate, pulls the plate back into position between the flanges of the rollers and a further movement of the lifter downward disengages the lip 105 from the groove.

Pivoted by studs 85 fastened in the lifter are spring rods 86 which operate through a rock roller 87 pivoted to levers 88 mounted on a shaft 89 supported by bearings on the frame. Mounted upon the rods are adjustable compression springs 90, the purpose of which is to compensate for any variation in the circumference of the stereotype plate. To one end of the shaft 89 is fastened a lever arm 91 to which is pivoted a link 92 by one end, the opposite end engaging with a cam 93 fastened to the main shaft. For the purpose of holding this arm 91 in position one end of a link 94 is pivoted to it, 110 120 125 130

the opposite end being pivoted to a cross piece of the frame. The cam roller rests in a recess in the side of the cam and upon turning the main shaft the recess moves 5 from over the roller, the roller thereby being depressed which act causes the lifter to rise. The return movement is accomplished by gravity.

Having described the mechanism for lifting the stereotype into the dome of the arch and shaving its ribs I will now describe the 10 riser separating and beveling mechanism and means for conveying and ejecting the riser from the machine, reference being had 15 especially to Figs. 8 to 13.

For the riser separating and trimming operation I employ a planetary mechanism in which is operatively mounted a revolving circular saw 100 having one of its edges 20 beveled for the purpose of forming a bevel on that edge of the stereotype plate from which the riser has been separated.

This planetary mechanism comprises a bracket 101 fixed to the main shaft by an 25 extension 102 at one end. The other portion is formed into a convex-concave shell with both ends closed. Extending through the shell and mounted in suitable bearings 30 is a short shaft, 103 to one end of which is attached the beveled edge saw 100 with its bevel facing adjacent to the lower end of the stereotype plate supporting arch. Facing 35 that closed end it is shaped so as to pass outside of and over the end of the arch. To the opposite end of the shaft 103, which extends through that end of the shell is keyed a gear wheel 104, which meshes with a gear 105 mounted on a stud 106 fastened in the bracket 101. Mounted on the main 40 shaft is another gear 108, which in turn meshes with the gear 105. Also mounted on the main shaft is a chain drive gear 109. Beneath the frame is a bracket 110 in which is mounted a shaft 111, having a chain 45 drive gear 112, fastened on each end and in brackets 113 at the back and alined with the frame is the driving shaft 58, which, through the chain connections, operates the two sets of chain gear drives and the beveled edged saw at a high rate of speed.

A portion of the shell of the saw bracket 101 is made loose and attached by hinged joints 115, to the fixed part of the said shell and to the loose edge of the hinged part of 55 the shell is connected a flat piece 116 of steel having its extending edge formed into short teeth 117 (Fig. 1) for the purpose of holding the riser after it has been separated from the stereotype plate as hereafter 60 shown.

Fastened on the main shaft 58 is a semi-circular riser support 120, which is so positioned that when the shaft turns it will pass under the riser of the stereotype plate, and 65 support the riser after it is separated by

the saw from its plate. During the operation of sawing away the riser from the stereotype plate the planetary shell 101 passes over the surface of the riser until the saw has finished the cutting operation when 70 the separated riser now resting on the support begins to turn with said support and planetary shell, but as the revolution continues from the position shown in Fig. 12 to that in Fig. 13 the loose riser has a tendency 75 to slip ahead. This is resisted by the fact that the riser is in contact with the teeth in the hinged portion of the shell. As the turning continues the weight of the riser is transferred from the support to said teeth 80 of the hinged portion of the shell and is carried ahead with said shell until the pivot point of the hinge has been passed on the upward motion when the said hinged portion tips over on its hinge and allows the 85 riser to drop free from its conveying mechanism. (See Fig. 9.)

It will be seen that the concavity of the saw bracket 101 serves the purpose of a saw-dust receiver. The dust is carried along 90 between the shell and the riser until the said riser is ejected by the opening out of the hinged shell, whereupon the sawdust escapes.

Mounted upon the saw bracket opposite 95 the saw is a plate supporting roller 121. Alined with the rollers on that side of the machine and mounted in the frame opposite is a similar roller 122 which, with the rollers within the arch and upon the main shaft, 100 forms conveying means for the discharge of the stereotype plate directly on the cooling saddle 170 the end of which is in alinement with said rollers.

Having described the construction and 105 operation of the shaving and trimming mechanism I will now describe the mechanism shown for operating the same. (See Figs. 14 and 21).

Keyed to the lower end of what I call the 110 main shaft 58, that is, the main shaft of the finishing device, is a large worm gear 125 which for the purpose of preventing accident is made in two parts, one of which is a toothed rim 126 mounted upon a hub 127, 115 which has a broad flange 128 facing the said ring. The rim and hub are made to travel together by a breaking pin 129 positioned in a hole through both members. The reason for making the gear in two parts is to 120 prevent accident in case the main shaft should for any reason be prevented from moving with the gear in which case as constructed the pin 129 would be cut in two and no other damage done.

Positioned below the worm gear and loosely mounted on a cross shaft 131, so as to mesh with the gear teeth is a worm 132. One end of it is formed with a clutch jaw 133. Mounted on the same shaft and facing 130

the jaw 133 of the worm is a sliding jaw 134 which is made to revolve with the shaft. Pivoted below this jaw on a stud 135 fastened in a leg of the frame is a shifting yoke 136 carrying projections 137 which engage in a groove 138 made around the sliding jaw member. One of the arms of the yoke extends upward and mounted on a stud 139 in said extension is a small roller 140. To the face of the worm gear 125 is pivoted a latch 142 positioned so that after each revolution of the worm gear it will engage the roller 140 and force the jaws of the sliding clutch out of engagement with the jaws of the worm, and hold them disengaged until the latch is moved on its pivot out of engagement with the yoke extension roller 140. The yoke at all times is held toward the engaging position by a compressed spring mounted on a rod 144 operating through a bracket 145 on the frame, the rod being attached to the yoke extension 136.

25 A trip mechanism for disengaging the latch 142 is located so as to push the said latch up and free from the yoke extension roller which consists of an upright rod 148, operating in bearings on a leg of the frame and carrying on its top an extension 149 with a beveled side 147. This extension when pushed up a short way engages with a pin 150 on the side of the latch which raises said latch and releases the yoke 136. Then the spring 151 will move the same which in turn advances the sliding jaw into engagement with the jaw on the worm.

It must be understood that the cross shaft 131 is revolved continuously by the driving shaft 152 to which it is connected by bevelled gears 155. The driving shaft is driven by any suitable source of power and connection, the motor K, belt, and pulley 154, on the shaft 152, being shown for this purpose.

45 The means employed for operating the trip rod 148 consists of a short lever 156, fast on a rod 157, operating in bearings and extending lengthwise of the machine and located at the back side but beneath the frame. To the opposite end of this rod is fastened an arm 158 (Fig. 2) which extends toward the front side of the machine. To the base C of the casting mechanism is pivoted on a stud a foot pedal 159 having an 50 extending arm which engages the arm on the aforesaid shaft.

By this mechanism the operator by pushing the pedal down can force the pawl out of engagement with the yoke extension and thereby start the machine, but in case he wishes to stop the machine for any reason before the trip acts, a second push downward will force the beveled edge 147 of the extension of the cam 149 up into engagement with the yoke extension roller 140 and

force the jaws of the clutch out of engagement. A spring 160 is mounted on the upright trip rod for the purpose of holding the said rod down and out of the path of the latch when the machine is in operation, and returning the pedal to its normal raised position. 70

Having explained the finishing of the curved stereotype plate I will now describe the improved flexible cooling and drying 75 mechanism employed, and explain how by controlling the contraction of the stereotype plate during the cooling process I am able to produce plates of both less or greater diameter from the same casting chamber, 80 also how by the control of the cooling water I can produce the plate dry and ready for the press cylinders.

Curved stereotype plates, such as are used in producing newspapers, are of a semi-circumference equal to the length of the printed matter of a newspaper page, and vary in diameter from $13\frac{1}{2}$ to $16\frac{1}{2}$ inches. 85

It is often found that although the printing faces of two different makes of web perfecting presses are the same yet the cylinders may vary in diameter an eighth of an inch, more or less, the difference being in the margins or space between the two printing halves of the circumference of the cylinders 90 which form the top and bottom blank space or margins of the paper. 95

Owing to this variation it has heretofore been necessary to cast the plates in machines for each size, and again owing to there being 100 a large variety of sizes of presses between the $13\frac{1}{2}$ and $16\frac{1}{2}$ (about 20) it has been considered impracticable to carry casting and finishing machines, in stock. These difficulties I am now able to overcome. 105

I find that an average sized curved stereotype plate will suddenly contract about $\frac{1}{2}$ " in diameter when the cooling water engages its concavity, and as the cooling advances from the concave side through to the exterior the plate will slowly contract on the outside and counteract the interior contraction, and if left perfectly free the plate will resume its normal curvature. However if the curved plate is supported in a manner 110 so its straight edges are held against axial contraction during the cooling of the interior surface it will nevertheless contract on the exterior and through this contraction cause the straight edges of the plate to draw away 115 from its axis and thereby become of a larger diameter than when cast. By utilizing and controlling this contraction I am able to produce plates of all sizes from four sizes of stock machines. 120

To accomplish this control of the contraction I have made the cooling saddle 176 (Fig. 2) with flexible sides or wings 171 (Figs. 14 to 20) arranged so as to contract or expand with the plate during the cooling 130

operation, the wings 171 are composed of spring metal, and are normally of a curvature slightly smaller than the diameter of the concave face of the finished ribs P' on the interior of the stereotype plate P. They are fixed to the sides of an overflow outlet 173 of a water distributing chamber 174 which is supported by pivots 175 on the frame G. The water chamber 174 is connected by a flexible tube 176, to a supply pipe 177 and a water controlling valve 178.

At each straight side of the wings are mounted rollers 180 for supporting the stereotype plate as it is delivered by gravity from the finishing mechanism. Also mounted on each straight side of the wings are brackets 181 (Figs. 16 to 19), which extend beneath the edges of the stereotype plate and have a lip 182 extending up so as to engage the outside edge of the stereotype plate. Beneath the wing brackets and supported by the frame are adjustable stops 183 which engage grooves 184, in the underside of the wing brackets when the stereotype has contracted or expanded the required amount as hereafter described.

The pivoted cooler, plate rollers, and brackets are normally held on the same angle as the main shaft of the finishing mechanism by a spring 186 attached to an arm 187 fast to the pivot 175, and a pivoted latch 189, is arranged to hold it at that angle during the delivery of the stereotype plate, but as the said plate positions itself by sliding down over the rollers from the finishing mechanism the beveled end of the plate engages the said latch and lifts it up (Fig. 14). This releases it from engagement with the cooler whereupon the cooler and plate will turn to horizontal position owing to the greater portion of the stereotype plate being beyond the pivot point. When the plate is lifted by hand from the cooler the spring 186 rocks the cooler back to the inclined receiving position shown in Fig. 14.

The balanced valve 178 is positioned in the water connections so that its plunger 191 can be operated by a lever 192 attached to the pivot 175, of the cooler. To one end 50 of the plunger is fastened a rod 194, operating in a bearing. It is provided with a spring actuated latch 195 in the path of a pin 196, positioned upon the lever 192 so that when the cooler turns on its pivot the 55 pin engages the latch and opens the valve allowing the water to flow up into the cooler water distributing chamber and overflow between the hot stereotype plate and flexible wings. As the outlet for the water 60 is confined to the space between the wings 171 and concave face of the stereotype plate, which space is less in cross section than the inlet, the water will be held under pressure against the stereotype plate and drive ahead 65 any steam that may form thereby causing

very quick action in cooling the stereotype plate. A stop 199 limits the rocking of the saddle.

For the purpose of stopping the flow of water before the stereotype plate is entirely 70 cold and allowing it to drain free from the plate so that the heat remaining will evaporate any moisture remaining, any desired construction can be used as for instance, a valve which opens automatically in a given 75 time, but I have shown a friction driven timing mechanism composed of a wheel 200, mounted on a stud 201 on an arm 202. This arm is pivoted to the frame G, by a stud 203. This wheel is intermittently driven 80 by a small pin 204, axially mounted on the end of the worm cross shaft 131. Normally facing this pin is a recess 206 formed across the face of the wheel. To the side of the wheel is fixed a pin 207 which is engaged by 85 a projection 208 formed on the lower end of the arm 192, and positioned so that as the cooler turns to horizontal position it will cause the said projection to engage the pin and turn the wheel ahead so that pin 204, 90 normally revolving in the recess 206 engages the face of the wheel 200, and causes said wheel to make one revolution. At the end of the revolution a second pin 210 engages 95 and trips the valve plunger latch 195, which action causes the valve to close and the flow of water to stop. A drip opening 211 is positioned near the overflow of the cooler which allows all water above the said drip to escape so that when the stereotype plate is 100 being lifted, (which action allows the cooler to be turned by its spring 186 into alignment with the main shaft and in position to receive the following stereotype plate,) there is no danger of splashing the stereotype 105 which is now cooled and dried.

By this combination of water control I not only require less water, as by actual test a plate can be sufficiently cooled after a water contact of three seconds, and a draining and 110 evaporating lapse of three seconds more, but also I succeed in cooling the stereotype plate so it can be removed from the cooler by the bare hands. This regulation of the water dispenses with brushes or any other means 115 of wiping the plate dry as has been the practice heretofore.

During the cooling operation, as stated, the stereotype plate contracts first on the interior and then, as the cooling advances 120 through the plate, on the exterior. This is due to the cooling water engaging the concavity of the stereotype only.

The means employed for controlling the contraction as previously stated comprises 125 adjustable stops 183 which engage the brackets 181 attached to the flexible wings of the cooler, the stereotype plate being held against the wings by projections 182 on the bracket overlapping the straight edges of 130

the stereotype plate. So if it is desired to reduce the curvature the adjustable stops are axially moved to the diameter desired so when the hot plate rolls down over the cooler and trips the latch 189 the cooler turns on its pivot until the groove 184 of the bracket 181 engages the top of a lip 217 (Figs. 17 to 19) of the adjustable stop. The act of tipping the cooler having opened the valve, the water rushes into contact with the concave side of the stereotype plate which causes the inside of the stereotype plate to contract, thereby reducing the diameter. This causes the wings carrying the grooved bracket to move axially inward until the groove 184 is over the lip 217 of the adjustable stop, whereupon the weight of the stereotype plate causes the cooler to turn on its pivots. This allows the lip to enter and engage the groove thereby holding the stereotype plate and wings against any further flexing of the stereotype plate in either direction, and thereby leaving the stereotype of a less diameter than when cast. To cause the stereotype to be of a greater diameter after cooling than when cast, the adjustable stop 183 is moved axially out to the desired diameter. If the full limit of expansion is required the stop is moved so it will engage the projection 219 on the lower side of the bracket 181 which will prevent any interior contractions, but as the exterior cools the contraction on the outer side will cause the stereotype plate to open out until the lip of the adjustable stop engages the groove as in the opposite operation. However if a lesser expansion of the diameter is desired the stop should be moved out less, then the action will be, first an interior and closing-in contraction which will cause the projection 219 on the bracket to engage the stop 183, and upon the exterior contraction taking place the stereotype plate will expand until the lip of the adjustable stop enters the groove of the bracket and resists further expansion of the diameter of the stereotype plate. If the plate is cooled on the exterior instead of on the interior the process will be modified accordingly.

Beneath the cooler a sink 220 is formed for catching the waste water which sink is provided with a pipe 221 for carrying the water away.

While I have illustrated and described a preferred embodiment of the invention I am aware that many modifications can be made therein by any person skilled in the art without departing from the scope of the invention. Therefore I do not wish to be limited to all the details of construction herein shown and described except as defined in the appended claims, but what I claim is:—

1. In a stereotype plate finishing machine, the combination of a shaft having finishing

devices, with axially movable supports carried on transverse axes by said shaft for supporting a printing plate.

2. In a stereotype plate finishing machine, the combination with a shaft, finishing devices connected with said shaft, rollers carried by said shaft for supporting the edges of the plate when introduced into the finishing machine, and means for retracting said rollers inwardly. 75

3. In a stereotype plate finishing machine, the combination of an arch, a shaft having finishing devices located adjacent to the arch, rollers on the shaft for receiving the plate, means for clamping the plate in the arch, and means for retracting the rollers inwardly so that the shaft can rotate and the rollers can pass around inside the plate. 80

4. In a stereotype plate finishing machine, the combination of a shaft, finishing means carried thereby, and two series of rollers arranged along opposite sides of said shaft rotatable on axes transverse to the axis of said shaft, and means for withdrawing said rollers inwardly along their axes. 85

5. In a stereotype plate finishing machine, the combination of a shaft having finishing devices, a series of rollers mounted thereon, a reciprocable cam, and means connected with said cam for moving the rollers transversely to the axis of said shaft. 90

6. In a stereotype plate finishing machine, the combination of a rotary shaft having finishing devices, rollers carried by said shaft for supporting the edges of a concave plate, a fixed cam, movable means carried by the shaft for engaging the cam as the shaft rotates, and a second cam movable with said movable means and provided with cam slots in position to retract said rollers axially as the shaft rotates. 100

7. In a stereotype plate finishing machine, the combination of a shaft, finishing means carried thereby, two series of idle anti-friction rollers arranged along opposite sides of said shaft rotatable on axes transverse to the axis of said shaft, a shaving arch above the shaft, and means for raising one edge of the plate from the rollers on one side, tipping its opposite edge about the tops of the rollers on that side, and forcing it into close contact with the interior of said shaving arch. 110

8. In a device for cooling stereotype plates, the combination of means for directing cooling water on the surface thereof, and means for automatically shutting off the water at a predetermined time before the plate is entirely cooled and while it remains in the cooling device, whereby the heat left in the plate will evaporate the water left on the plate thereby drying its surface. 120

9. In a stereotype plate finishing machine, the combination of a concave arch, a shaft 130

extending longitudinally thereof and having finishing devices, means on said shaft for supporting both edges of the printing plate when it leaves the arch, supports for 5 one edge of the plate along one edge of said arch, and means for lifting the opposite edge of said plate and forcing it into the arch and clamping it there with the first named edge in contact with the supports at 10 the other edge.

10. In a stereotype plate finishing machine, the combination of a concave arch, a shaft extending longitudinally thereof and having finishing devices, rollers on said 15 shaft for supporting both edges of the printing plate, roller supports for the plate along the sides of said arch, and means for lifting one edge of said plate and forcing it into the arch and clamping it there with the 20 other edge in contact with the rollers at the other side.

11. In a stereotype plate finishing machine, the combination of a concave arch, a shaft extending longitudinally thereof and having finishing devices, rollers on said 25 shaft for supporting both edges of the printing plate, means for lifting one edge of said plate and forcing it into the arch, and means for withdrawing the rollers on 30 the shaft inwardly to allow them to rotate inside the concave plate.

12. In a stereotype plate finishing machine, the combination with an inclined finishing arch, of a cooling device arranged 35 at the lower end thereof to receive plates therefrom and having means for supporting the plates therein in position with their lower straight edges located at an angle to the inclination of the arch, and means adjacent to said supporting means for holding 40 the plates in fixed position while being cooled.

13. In a stereotype plate finishing machine, the combination of an arch for receiving a segmental plate, flanged rollers located along one side of the arch for temporarily receiving and guiding the plate 45 into the arch, a plate support located along the other side of the arch for the opposite edge of the plate, and a plate lifter located adjacent to said flanged rollers and movable upwardly toward the arch at an inclination to the vertical for tilting the plate about said support.

55 14. In a stereotype plate finishing machine, the combination of an arch for receiving a segmental plate, means for receiving one side of the plate and guiding it into the arch, a plate support located along the 60 other side of the arch for the opposite edge of the plate, a plate lifter located adjacent to said plate support and movable upwardly toward the arch, a cam, connections from said cam for operating said plate lifter positively and swinging the plate into the arch

about an axis, and resilient means for returning the plate lifter to retracted position.

15. In a stereotype plate finishing machine, the combination of a plate lifter having a projecting lip rigidly mounted thereon 70 for engaging a groove in the edge of the cast plate, and separate means in position to receive the edge of the plate when pulled back by the retractive movement of said lip.

16. In a stereotype plate finishing machine, the combination with an arch, of a plate lifter for one side of the arch adapted to move into the arch and seat a plate therein, said plate lifter having a projecting lip for engaging a groove in the edge of the 80 cast plate, and flanged rollers within the arch in position to receive the edge of the plate when pulled back by the retractive movement of said lip.

17. In a stereotype plate finishing machine, the combination with an arch adapted to receive a segmental stereotype printing plate and a rotary shaft for carrying finishing tools, of adjustable plate stops near the end of said arch and in position to engage 90 lugs on the inside of the riser of the plate, said stops being arranged to stop the plate and prevent lateral movement thereof while the lugs are in engagement with them.

18. In a stereotype plate finishing machine, the combination with an arch adapted to receive a segmental stereotype printing plate, of adjustable plate stops in position to engage lugs on the inside of the plate, one of said stops being resiliently actuated 100 to permit the movement of the plate sideways into axial alignment with the arch.

19. In a machine for finishing stereotype printing plates, the combination with an inclined finishing arch, of a cooling device for 105 the plates having supports for holding the plates in horizontal position after they come from the arch.

20. In a stereotype plate finishing machine, the combination with a shaving arch, 110 of a longitudinal shaft therein, means for supporting a stereotype plate therein, means whereby the shaft will rotate through a complete revolution and then automatically stop, a cutter connected with the shaft for 115 cutting off the riser of the plate, and means for holding the riser on the supporting means until it revolves beneath the supporting means and thereafter delivering said riser from the mechanism.

120 21. In a stereotype plate finishing apparatus, the combination with a shaving arch, of a longitudinal shaft therein, means for supporting a stereotype plate therein, a trip, means whereby upon the operation of the 125 trip the shaft will rotate through a complete revolution and then automatically stop, a cutter connected with the shaft for cutting off the riser of the plate, means carried by the shaft for supporting the riser 130

- when it is cut off, and means for holding the riser in the supporting means until it revolves beneath the supporting means and thereafter delivering said riser from the mechanism.
22. In a stereotype plate finishing apparatus, the combination with a shaving arch, of a cutter for cutting off the riser of the plate, means for supporting the riser when it is cut off, and means for holding the riser in the supporting means until it revolves beneath the supporting means and thereafter delivering said riser from the mechanism.
23. A cooling device for plates having means for supporting the plates in horizontal position, and means adjacent thereto for holding the edges of the plates in fixed position while being cooled.
24. In a stereotype plate finishing machine, the combination of a rotatable shaft, means for supporting a curved stereotype plate, means for cutting the riser from the plate as the shaft rotates, a riser support fixedly mounted with respect to said shaft, and a riser holding means carried around with the shaft.
25. In a stereotype plate finishing machine, the combination of a shaft, means for supporting a curved plate above the same, a saw for cutting the riser from said plate, and a pivoted member carried around with the shaft for engaging the riser and supporting and delivering it after it is separated from the plate.
26. In a stereotype plate finishing machine, the combination of a shaft, means for supporting a curved plate above the same, a saw for cutting the riser from said plate, and a member carried around with the shaft and pivoted on an axis parallel with the shaft for engaging the riser and supporting and delivering it after it is separated from the plate.
27. In a stereotype plate finishing machine, the combination with a shaft, of a semi-circular riser support carried by the shaft in position to pass between the shaft and riser as the shaft turns and to support the riser after it is separated from the plate, a saw for separating the riser from the plate, and means carried by the shaft for rotating the separated riser with the support as soon as it is separated from the plate.
28. In a stereotype plate finishing machine, the combination of a shaft, finishing mechanism comprising means for cutting a riser from a plate as the shaft rotates, a riser support in position to pass under the riser while it is being separated, and a hinged member carried by said shaft in position to be dragged over the surface of the riser while the riser is being cut off and to hold the riser when it is separated from the plate, whereby as the revolution

of the shaft continues the loose riser, normally tending to slip downward ahead of the shaft, will be forced into tight engagement with the hinged member, and held thereby.

29. In a stereotype plate finishing machine, the combination of a shaft, a support adjacent to the shaft for a curved stereotype plate, means for cutting the riser from the plate as the shaft rotates, a riser support carried by the shaft, and a member pivoted on said shaft in such position that at the end of the cutting operation said member will engage the riser and prevent it suddenly dropping from the machine, whereby as the turning motion continues the weight of the riser is transferred from the support to the pivoted member and carried ahead thereby until it passes over the pivotal point of the pivoted member when it swings the same and drops free from the machine.

30. In a stereotype plate making machine, the combination of an inclined rotary shaft, means for cutting the riser off the plate, supports carried by the shaft, and means for moving said supports longitudinally with respect to the shaft into a position to support the edges of the plate after the riser is cut off so as to deliver the plate.

31. In a stereotype plate finishing machine, the combination of a shaft, means connected therewith for cutting the riser off the plate, means adjacent to the shaft for supporting the plate, and a saw-dust receiver carried around with the shaft for receiving the saw-dust, carrying it part way around with the shaft, and depositing it.

32. In a stereotype plate finishing machine, the combination of a shaft, means connected therewith for trimming the edge of the plate, means for supporting the plate, and a saw-dust receiver carried around with the shaft.

33. In a device for preparing stereotype printing plates, the combination with a finishing mechanism located at an inclination, and a cooling mechanism located at the lower end of the finishing mechanism in position to receive plates delivered therefrom by gravity, and provided with a rocking support for the plates adapted to move the plates into horizontal position after they have been delivered to the cooling device.

34. In a device for preparing stereotype printing plates, the combination with a finishing device, of a cooling device having supports mounted on an incline, in position to receive the edges of the plate delivered from the finishing device and adapted to be moved into a horizontal position by the weight of the plate supported thereon.

35. In a device for cooling stereotype printing plates, the combination of a pivoted saddle for receiving the plate, yielding means for normally holding said saddle at an inclination to the horizontal, means for positively holding the saddle at said inclination, the last named means being located in position to be engaged by the plate when it slides down the inclination to its final resting place and to be disengaged thereby, and means for allowing the saddle to be freed.

36. In a device for cooling stereotype printing plates, the combination of a pivoted saddle for receiving the plate, yielding means for normally holding said saddle at an inclination to the horizontal, a latch for positively holding the saddle at said inclination in position to be engaged by the plate when it slides down the inclination to its final resting place and to be disengaged thereby, and means controlled by said latch for allowing the saddle to be turned by the weight of the plate.

37. In a stereotype plate cooling apparatus, the combination of an inclined guide-way, a pivoted cooler mounted normally in alinement with said guide-way to receive a plate therefrom, and a latch for holding said pivoted cooler in alinement with the guide-way, said cooler being pivoted at a point on the side of its center of gravity opposite that on which said latch is located.

38. In a stereotype plate cooling apparatus, the combination of an inclined guide-way, a cooler mounted normally in alinement with said guide-way to receive a plate therefrom, a latch for holding said cooler in alinement with the guide-way, said cooler being pivoted at a point between the latch and its center of gravity, said latch being located in position to be engaged by the plate when it slides down to the end of the cooler and released, whereby the plate will be turned on the pivot to a horizontal position, and means for stopping the cooler in horizontal position.

39. In a cooling device for stereotype printing plates, the combination with a supply pipe, of a valve for controlling the same, a cooler for supporting the plate, means whereby after the plate is located on the cooler the valve will be opened automatically to allow the water to flow into the cooler, and a trip mechanism for causing the valve to close while the plate is on the cooler.

40. In a cooling device for stereotype printing plates, the combination with a supply pipe, of a valve for controlling the same, a lever for operating the valve, a cooler for supporting the plate, means whereby when the plate is located on the cooler it will turn on an axis, a latch in position to be engaged by a part of said cooler

when it turns, means connecting the latch and lever for opening the valve when the latch is thus operated to allow the water to flow into the cooler, and a trip mechanism for disengaging the latch.

70

41. In a cooling device for stereotype printing plates, the combination with a supply pipe, of a valve for controlling the same, a lever for operating the valve, a cooler for supporting the plate, means whereby when the plate is located on the cooler it will move the lever for opening the valve to allow the water to flow into the cooler, and means for automatically stopping the flow of the water while the plate remains in the same position.

75

42. In a cooling device for stereotype printing plates, the combination with a supply pipe, of a valve for controlling the same, a lever for operating the valve, a cooler for supporting the plate, means whereby when the plate is located on the cooler the cooler will move, a latch in position to be engaged by a part of said cooler when it moves, means connecting the latch and lever for opening the valve when the latch is thus operated to allow the water to flow into the cooler, and means for automatically stopping the flow of the water.

80

43. In a device for preparing stereotype printing plates, the combination with a finishing mechanism located at an inclination, and a cooling mechanism located at the lower end of the finishing mechanism in position to receive plates delivered therefrom by gravity and adapted to hold them in horizontal position.

95

44. In a cooling device for stereotype printing plates, the combination with a water supply pipe, of a valve for controlling the same, a lever for operating the valve, means for supporting a plate, a latch, means connecting the latch and lever for opening the valve to allow the water to flow, a wheel, means for rotating the wheel, means whereby when a plate enters the machine, the lever is moved and causes the wheel to rotate through one revolution, and means controlled by the rotation of said wheel for closing the valve and shutting off the water.

105

45. In a cooling device for stereotype printing plates, the combination with a water supply pipe, of a valve for controlling the same, a wheel, means for rotating the wheel, means whereby when a plate enters the machine the wheel will rotate through one revolution and stop at the end thereof, and means controlled by the rotation of said wheel for closing the valve and shutting off the water.

110

46. In a device for cooling stereotype printing plates, the combination of a water outlet, means for supporting a plate, and movable wings constructed and arranged to come into contact with the concave face of

130

a stereotype plate when in position to be cooled.

47. In a device for cooling stereotype printing plates, the combination of a cooling mechanism adapted to support a plate, flexible wings adapted to be received within the plate, adjustable stops for the wings, means whereby when a plate is introduced into the cooler it will cause the wings to tip on an axis, a valve for controlling the admission of a cooling fluid, and means whereby the tipping of the wings will open said valve.

48. In a device for cooling stereotype printing plates, the combination of a cooling mechanism adapted to support a plate, flexible wings adapted to be received within the plate, adjustable stops for the wings, means whereby when a plate is introduced into the cooler it will cause the wings to tip on an axis, a valve for controlling the admission of a cooling fluid, means whereby the tipping of the wings will open said valve, means for directing the water on the inside of the curved stereotype plate, and means for limiting the motion of the wings with the contraction of the plate.

49. In a device for cooling curved stereotype printing plates, the combination of a cooling saddle having flexible wings for receiving the plate to be cooled, said wings having brackets extending into position beneath the edges of a plate carried on the saddle and each having a lip extending up in position to engage the outer edge of the plate, and adjustable stops located below the said brackets adapted to be adjusted into position to engage the under sides of the winged brackets when the plate has contracted or expanded to the desired amount, whereby the amount of expansion or contraction of the curved plate and the distance apart of its straight edges can be limited.

50. In a device for cooling curved cast plates, the combination of a cooling saddle having flexible wings for receiving the plate to be cooled, said wings being arranged and adapted to contract and expand with the plate, and means for causing water to flow over said wings in contact with the interior of the plate and out of contact with the exterior convex surface thereof, said wings having brackets extending into position beneath the edges of a plate carried on the saddle and each bracket having a lip extending up in position to engage the outer edge of the plate.

51. In a device for cooling curved cast plates, the combination of a cooling saddle having flexible wings for receiving the plate to be cooled, said wings being arranged and adapted to contract and expand with

the plate, and means for causing water to flow over said wings and in contact with the interior of the plate.

52. In a device for cooling curved cast plates, the combination of a support for the plates, means for applying a stream of cooling fluid to the concave side of a plate, and means for holding its straight edges against axial contraction during the cooling of the interior surface to prevent the motion of said edges inwardly and leaving said edges free to expand or draw away from each other during the remainder of the cooling of the plate.

53. In a device for cooling curved cast plates, the combination of means for applying a stream of cooling fluid to the concave side of a plate, and means for holding its straight edges against lateral expansion during the cooling of its convex surface.

54. In a device for cooling curved cast plates, the combination of a support for the plates, means for applying a stream of cooling fluid to the concave side of a plate, and means for positively holding its straight edges against lateral contraction during the cooling of its concave surface.

55. In a device for cooling stereotype plates, the combination of a support for the plates, and a water distributing chamber adapted to contain a large body of water having outlets in position to discharge water and having a separate drain opening at a point below said outlets but above the bottom of the chamber.

56. In a machine for finishing curved stereotype printing plates, the combination of a knife for shaving out the interior of the plate, a saw located outside the plate for beveling the end edge of the plate, and means for giving the saw a planetary motion around the outside of the plate at the end thereof.

57. In a machine for finishing curved stereotype printing plates, the combination of a shaving blade for shaving out the interior of the plate, a saw located outside the plate rotatable with said shaving blade for cutting the tail from the plate, and means for giving the saw a planetary motion around the outside of the plate at the end thereof.

58. In a stereotype plate cooling apparatus, the combination of an inclined guideway, and a pivoted cooler mounted normally in alinement with said guideway in position to receive a plate therefrom.

In testimony whereof I have hereunto affixed my signature.

CHARLES E. HOPKINS.
